United States Patent Office

Des. 181,470

Patented Nov. 19, 1957

181,470

TEXTILE FABRIC OR SIMILAR ARTICLE

James G. Hardy, New York, N. Y., assignor to Realty
Hotels Incorporated, New York, N. Y.

Application May 31, 1956, Serial No. 41,706

Term of patent 14 years

(Cl. D92—1)

The figure is a plan view of a textile fabric showing one complete unit of my new design, said unit being repeated across the face of the fabric in regular succession.

I claim:

The ornamental design for a textile fabric or similar article, as shown and described.
